Primary Examiner — Stella Reid*Assistant Examiner* — Keli L Hill(74) *Attorney, Agent, or Firm* — Sterne, Kessler, Goldstein & Fox P.L.C.(57) **CLAIM**

The ornamental design for a shoe, as shown and described.

DESCRIPTION

FIG. 1 is a side view of a portion of a sidewall of a shoe sole showing my new design; and,

FIG. 2 is a bottom plan view thereof.

The dash-dot broken line immediately adjacent to the shaded areas represent the bounds of the claimed design while all other broken lines are included for the purpose of illustrating the unclaimed portions of the article the broken lines form no part of the claimed design.
